[57] **CLAIM**

The ornamental design for an element of a shoe upper, as shown and described.

DESCRIPTION

FIG. 1 is a left side elevational view of a shoe showing my new design;

FIG. 2 is a right side elevational view thereof;

FIG. 3 is a top plan view thereof.

The broken line showing of a shoe in FIGS. 1-3 is environmental only and forms no part of the claimed design.

FIG. 1

FIG. 2

FIG. 3
